NOVELTY TRACKWAY FOR GRAVITY- DEFYING ROLLING CONE

Jerome Cohen, 178 N. Pleasant Ave.,
Ridgewood, N.J. 07450

Filed Mar. 30, 1971, Ser. No. 129,656

Term of patent 14 years

Int. Cl. D21—01
U.S. Cl. D34—15 K

F I G . I

FIG. 2

FIG. 3

FIG. 5

FIG. 4

FIG. 1 is a perspective view of a novelty trackway for gravity-defying rolling cone showing my new design;
 FIG. 2 is a front view of the design shown in FIG. 1;

FIG. 3 is a top plan view of the design shown in FIG. 1;

FIG. 4 is a side view of the design shown in FIG. 1 taken from the left side of same; and

FIG. 5 is a side view of the design shown in FIG. 1 taken from the right side of same.

I claim:

The ornamental design for a novelty trackway for gravity-defying rolling cone, as shown and described.
